FURNACE CONSTRUCTION

Filed Oct. 27, 1920

Fig. 7.

UNITED STATES PATENT OFFICE.

ANDREW C. EDGAR, OF NEWTOWN SQUARE, PENNSYLVANIA.

FURNACE CONSTRUCTION.

Application filed October 27, 1920. Serial No. 420,065.

To all whom it may concern:

Be it known that I, ANDREW C. EDGAR, a citizen of the United States, residing at Newtown Square, in the county of Delaware 5 and State of Pennsylvania, have invented certain new and useful Improvements in Furnace Constructions, of which the following is a specification.

The object of this invention is to provide 10 improvements in boiler constructions, and with particular reference to the provision of a high temperature surface for igniting the gases of combustion as they unite with super-heated air entering the combustion chamber 15 at the proper points, and together impinge against said surface, to produce the greatest heat at the desired locality and also insure an absence of color or smoke as the products of combustion leave the exit.

Another object is to provide details of 20 construction which materially assist in accomplishing the foregoing object with the highest possible degree of efficiency, and to this end providing a suspended bridge-wall 25 comprising one or more sections of channelled fire-brick, slidably and removably inserted within the boiler, preferably through the side thereof and supported by integral parts of the boiler section, or sections, provided for the purpose.

Still another object is to provide fire-brick 30 sections for the purpose specified, the same being shaped as to be capable of use in one position within the upper portion of the combustion chamber of a boiler as a suspended bridge-wall, and equally well adapted for use in an inverted position when inserted in the lower portion of such a chamber for use in place of the common type of 40 bridge-wall intended to limit the extent of the fire-bed in one direction, and said sections being also adapted for simultaneous use in the same furnace, one as a lower bridge-wall at the grate level and the other 45 as an upper suspended bridge-wall, with sufficient distance separating them in such last arrangement as to freely pass the ignited gases of combustion therebetween.

And still another object is more specifically to provide fire-brick sections, each 50 comprising a body portion preferably tapered in cross-section in one direction, and provided with a longitudinally extending channel opening through the end portions 55 of the said section, with one or more branch

channels leading from said first channel and preferably tapering as they approach and open outwardly through restricted apertures in the tapered portion of the said section, one end of a section preferably being extended and axially bored in alignment with 60 said first channel, and operative to provide a suitable means for connecting an air-conducting pipe to said first channel.

And a still further object is to provide in 65 a sectional boiler two adjacent sections having co-operating recesses to jointly form an aperture in one side of the boiler, the adjacent sides of said recessed sections being provided with aligned brackets adapted to receive 70 slidably and removably support within the combustion chamber fire-brick sections of the character above referred to, after said sections have been inserted through said aperture, said aperture normally being closed 75 by means of a demountable plate or door when access to the interior of the boiler is not desired. And in combination with the said boiler section construction, there is provided an air flue adapted at one end to be 80 connected to lead air into the longitudinal channel of the fire-brick section when in normal position within the boiler, and at its other end preferably connected so as to draw air from the ash pit below the grate level. 85

With this construction, the flow of the air through said flue is adapted to be regulated by the same means such as a damper regulator, employed to regulate the consumption of the fuel upon the grate of the boiler, 90 while the air after leaving said flue enters the longitudinal channel of the high-temperature bridge-wall, whether at grate level, or suspended from above, or both in combination, and thence passes through the 95 said branch channels where it is super-heated before it enters the combustion chamber of the boiler and unites with the gases of combustion arising from the fuel being used, the combined gas and air in the proper 100 predetermined proportions igniting as they together impinge against the ignition surface of the bridge-wall.

With these and other objects in view, the invention consists in further details of construction and operation, which are fully brought out in the following description, when read in conjunction with the accompanying drawings, in which Fig. 1 is a 105 vertical transverse section of a boiler taken 110

between two adjacent sections and comprising one embodiment of the invention; Fig. 2 is a side elevation of the two sections between which the cross-sectional view Fig. 1 is taken; Fig. 3 is a view similar to Fig. 1 and representing a modified form of the invention; Fig. 4 is a side elevation of the two sections between which the cross-sectional view Fig. 1 is taken; Fig. 5 is a view similar to Fig. 1 and illustrating a second modification of the invention; Fig. 6 is a side elevation of the two sections between which the cross-sectional view Fig. 1 is taken; Fig. 7 is a continuation of the vertical longitudinal section of the construction shown in Figs. 1 and 2; and Fig. 8 is a similar view of the construction shown in Figs. 3 and 4.

Referring to Figs. 1 and 2 of the drawings, two adjacent sections 1 and 2 of a sectional end-feed boiler are shown, these being sufficient for the purpose of illustrating the application and functioning of the improved hollow tile bridge-wall construction with relation to boilers of this character. Each of said sections comprise laterally positioned vertically extending cored leg portions 3, connected at the top by a horizontally extending cored portion 4, provided with a plurality of apertures 5 which are in alignment in the several sections going to make up a complete boiler and are for the purpose of permitting drafts carrying the products of combustion to pass through the water-carrying portions of the said sections and by thus increasing the surface area, decreasing the time required for the water to absorb a given quantity of heat from the said drafts.

The lower portions of the said legs are provided with apertures into which are secured nipples 6 for connecting the sections together to aid in the more rapid circulation of the water than would otherwise be possible, if the leg portions were completely self-contained and independent of one another. The upper portions of the said sections are similarly joined by nipples 7, while the uppermost portions of the several sections are often provided with nipples 8, leading into a common longitudinally extending trunk pipe (not shown). When assembled as a complete boiler the sections referred to rest upon side castings 8^a, provided with apertures 9 and operatively supporting any suitable type of grate 10, while the chamber 11 inclosed by said castings constitutes the ash-pit, into which opens through one of the sides a draft inlet 12, covered by a pivotally mounted closure 13, which is arranged to be automatically opened and closed by means of a chain 14 connected at its upper end to the adjustably weighted lever 15 adapted in the usual manner to be actuated automatically by a

diaphragm within the casing 16 in accordance with the pressure of the steam within the boiler.

Each of the leg portions 3 of both of the sections 1 and 2 is provided with a pair of recesses 17 extending inwardly from one side, one being positioned adjacent to the lowermost portions of said legs, while the other is positioned adjacent to the uppermost portion thereof and terminating in alignment with the lower edge portion of the horizontally extending cored portion 4. Each of the said sections is furthermore provided with a horizontally extending integrally supported ledge 18, substantially midway between the upper and lower extent of the said recesses 17, and extend from one leg portion directly across to the other leg portion of each of said sections. The recesses in section 1 are illustrated in Fig. 2 as being positioned so as to register with the corresponding recesses in section 2, and when said sections are joined as shown in the drawings, said recesses together form a pair of apertures through the opposite sides of the boiler, said apertures being normally closed or covered by removable plates 19, supported and removably secured in position by means of bolts 20 or the like.

Adapted to be inserted through the said apertures and slidably upon the ledges 18 are cored sections 21 of fire-brick in transverse cross-section very closely conforming in shape and size to the corresponding dimensions of the said apertures, and in length when operatively positioned extending through the leg portions of the boiler sections upon one side of the boiler to and through the leg portions upon the opposite side of the boiler as shown in Fig. 1. These sections are interchangeable and are provided with longitudinally extending aligned channels 22, closely adjacent to one side surface of the fire brick, while branches 23 of said channels extend at right angles with the former and towards the opposite side surface of the fire-bricks, that portion of the bricks through which the branch channels emerge being transversely tapered so as to provide a blunt edge portion, past which the products of combustion must pass from the fire bed upon the grate 10 on their way through the flues of the boiler and toward the stack.

By reference to Fig. 1, the upper pair of fire-bricks will be seen to constitute a suspended bridge-wall, so designed and positioned as to absorb and retain sufficient heat to make the lower surfaces of the bricks comprise ignition surfaces, and, by reason of their great heat, considerably raising the temperature of the air passing through them downwardly as shown by the arrows and outwardly into the combustion chamber immediately therebelow. The lower fire-bricks also seen in Fig. 1 constitute a bridge-wall

against which the fuel upon the grate 10 is adapted to be fed, but in this latter instance the bricks and their respective surfaces are not raised to the same temperature as those immediately above, wherefore the branch channels 24 extending upwardly from longitudinally extending aligned channels 25 are tapered upwardly so that they will not choke with the deposit of dust which will obviously flow through them upon being fed into the channels 25 from the ash-pit as hereinafter described, and as would obviously be the case if the sides of the said branch channels were parallel.

The corresponding channels 23 in the upper bricks comprise a suspended bridge wall, it will be noted, taper downwardly, but this is of little or no consequence when occurring in a member that by actual design is so positioned as to present an ignition surface by reason of the high temperature at which it is maintained, said high temperature operating to consume and disintegrate any fuel or ash dust which may enter into the several channels passing therethrough.

Extending outwardly from the ash-pit 11 and secured within the apertures 9 are nipples 26 connected with T's 27, having their opposite end portion closed by plugs 28, and their laterally positioned openings connected by means of tubing 29 to the cross 30, one end of each of which latter is connected by a nipple 31 to an open end of the adjacent channel 25 and the lower bridge-wall fire bricks, and through the adjacent plate closure 19, the opposite opening of which cross is closed by means of a plug 32, while the fourth opening is connected by an upwardly extending tube 33 to the downwardly directed opening of a T 34, having a second opening connected by means of a nipple 35 to the adjacent end of the horizontal channel 22 within the fire-bricks of the suspended bridge-wall, the third and last opening of said last-named T being closed by means of a plug 36.

When in operation, the furnace equipped as before described is automatically regulated by reason of the steam pressure actuating the lever 15, with the result that when the temperature of the fire falls, as evidenced by the decrease in steam pressure, the door 13 is opened and the fire permitted to burn, thereby creating a more rapid production of the products of combustion from the fuel within the combustion chamber. The opening of the door 13 to permit the entrance of air therethrough to the grate and the fire-bed thereupon, fresh air is also admitted to the nipples 26 and other flue connections to the fire-brick channels 22 and 25, so that as a result there is an increase in the flow of air through the branch channels 23 and 24 also in the combustion chamber of the boiler, this flow of preheated air through the cored

fire-brick being maintained in substantially constant proportion to the rate of combustion of the fuel upon the grate 10.

It is obvious from the construction illustrated that in the event of any of these said bricks becoming damaged or broken, the same may be replaced by removing the adjacent closure plates and removing the desired brick through the corresponding apertures 17-17, and after insertion of a new brick, replacing the said plate and recoupling the fresh air connections to the said brick.

Referring now to Figs. 3 and 4, a portion of a furnace is shown similar to that described, in that it comprises two of the sections 37 and 38 of a boiler provided with leg portions 39 and a horizontally extending cored section 40 at the upper end thereof, the leg sections being connected to one another by means of nipples 41 and the uppermost portions of said sections connected together by nipples 42, while the leg portions of each of these two sections of the furnace are connected by a transversely extending cored bridge-wall 43. These sections as in the first instance rest upon castings 44 inclosing an ash-pit 45, above which is a grate 46, while an inlet 47 is provided in said ash-pit, the opening of which is regulated by means of a door 48 connected by a chain 49 to the lever 50 of the diaphragm-actuating means within a casing 51 upon the upper portion of one of the boiler sections above the water level.

These two sections are formed with cooperating recesses 52, which together form apertures in the opposite sides of the boiler when assembled, and through which fire-bricks 53 can be inserted slidably upon transversely extending ledges 54. These said fire-bricks comprise aligned longitudinally extending channels 55, from which branch channels 56 extend downwardly into the combustion chamber 57 of the boiler, the longitudinally extending channels being connected at their outer free ends through plate closures 58 with nipples 59 and T's 60 to vertically extending tubes 61, which at their lower ends are connected through T's 62 to nipples 63, which lead directly through apertures 64 in the castings 44 into the ash-pit 45.

With this construction the suspended bridge-wall has the same functions exactly as those described in relation to the first form of furnace construction illustrated, the only difference that the furnace, in the present case, instead of being provided with a replaceable cored fire-brick bridge-wall, against which the fuel is fed, has the cored iron bridge-wall 43, showing that manufacturers who at the present time produce furnaces with the cored bridge-wall need not, if they so desire, make much alteration to

their furnaces in order to incorporate in them the present invention relating to the cored interchangeable sections.

Referring now to Figs. 5 and 6, the type 5 of end feed boiler is shown as comprising oppositely positioned vertically extending leg portions 67, connected to one another at their lower extent by nipples 68, while said sections at their uppermost portions are

10 connected together by adjacent sections by means of nipples 69, each of said sections at its upper portion comprising a horizontally extending cored section 70, and a cored water-cooling suspended bridge-wall 71, 15 which, unlike the corresponding bridge-walls hereinbefore described, does not offer an ignition surface for the gases of combustion within the combustion chamber of the boiler.

20 This last-named furnace furthermore comprises an ash-pit 72 inclosed by a casting 73, through which leads an inlet 74, the opening of which is adapted to be altered by means of a closure 75 connected by a chain 25 76 to the usual weighted lever 77, operated by means of a diaphragm within a casing 78 positioned upon an upper portion of a boiler section above the water limit within. The upper end portions of the ash-pit 30 castings 73 are spanned by a grate 79, while directly upon said castings rest the several boiler sections. Each of said sections is provided in the lowermost portions of its legs 67 with co-operating recesses 80, which 35 together form apertures through which may be inserted into the boiler the removable and interchangeable sections of cored fire-brick 81, said apertures being normally closed by means of plates 82 supported and 40 secured in position by means of bolts or the like 83. These last-named fire-bricks embody aligned longitudinally extending channels 83, from which rises upwardly tapering branch channels 84 similar in every way to 45 those described with relation to Figs. 1 and 2, and functioning in exactly the same manner.

Having thus described my invention, what I claim and desire to protect by Letters Patent of the United States is:—

1. A fire-brick, provided with a longitudinally extending channel opening through the opposite ends thereof, with a branch channel leading from said first channel and 55 opening through a laterally positioned surface thereof, and with a pair of parallel grooves forming shoulders positioned upon the opposite sides of the said brick to engage means to operatively support said 60 brick within the combustion chamber of a boiler.

2. The combination of a boiler, and supporting means carried by the boiler, with a fire brick removably mounted upon said 65 means and provided with a longitudinal

channel, and with a branch channel opening through a surface to the said brick laterally disposed with relation to the said first channel and adapted to lead air from said first channel into the combustion chamber of the 70 boiler and hollow air-conducting means connected with, and operative to lead air from, the ash-pit of the boiler into the first of said channels of said brick.

3. The combination of a boiler, having an 75 opening and supporting means within said boiler terminating adjacent to said opening, with a fire brick adapted to be inserted through said opening upon and removably supported by said means within the combustion chamber of the boiler, said brick being provided with a channel connecting with the outside of said boiler through said opening, and with a branch channel extending from said first channel to and through a side of 85 the said brick laterally disposed with respect to said first channel, and hollow air-conducting means connected with, and operative to lead air from, the ash-pit of the boiler into the first of said channels of said brick. 90

4. The combination of a boiler, having an opening and supporting means within said boiler terminating adjacent to said opening, with a fire brick adapted to be inserted through said opening upon and removably 95 supported by said means to extend within the combustion chamber of the boiler, said brick being provided with a channel leading from the side adjacent to the said opening and terminating through a surface forming 100 a portion of the ignition surface of the brick within said chamber, and tubular means extending from said channel through said opening outside of said boiler and into the ash-pit of the boiler to lead preheated air 105 from said ash-pit into the channel of said brick from delivery into said combustion chamber.

5. The combination of a boiler, having an opening supporting means within said 110 boiler, with a fire brick adapted to be inserted through said opening and removably supported by said means to extend within the combustion chamber of the boiler, said brick being provided with a channel leading from 115 the side adjacent to the said opening and terminating through a surface forming a portion of the ignition surface of the brick within said chamber, said channel being adapted to lead air into said chamber from 120 said opening, and a pipe connection between the said channel of the fire brick and the ash pit of the boiler.

6. The combination of a boiler, with an opening in the upper portion thereof, and an opening in the lower portion thereof, supporting means within said boiler terminating adjacent to and accessible from said openings, and a fire-brick adapted to be interchangeably positioned upon either of said 130

supporting means, to form either a bridge-wall at grate level or a suspended ignition surface within the combustion chamber of the boiler.

- 5 7. The combination of a boiler, with an opening in the upper portion thereof, an opening in the lower portion thereof, supporting means within said boiler terminating adjacent to and accessible from said
- 10 openings, fire-bricks upon said means and provided with channels adapted to take in air through said openings, and to pre-heat the air before it leaves said channels through a portion of the high-temperatured ignition
- 15 surfaces of the said bricks and passes into the combustion chamber of the boiler and a hollow flue connecting the said channels through said openings with the ash-pit of the boiler.

8. The combination of a boiler, with oppositely positioned openings in the upper portion thereof, oppositely positioned openings in the lower portion thereof, supporting means within said boiler accessible from each of said openings, and fire-bricks upon said means removable through said openings and provided with channels adapted to take in air through said openings, and to pre-heat the air before it leaves said channels through a portion of the high-temperatured ignition surfaces of the said bricks and passes into the combustion chamber of the boiler, and hollow connections whereby air is led from the ash-pit of the boiler into the opposite ends of each of said channels.

In testimony whereof I have affixed my signature.

ANDREW C. EDGAR.
